SEWING MACHINE

Andrew B. Clayton, Union, N. J., assignor to The
Singer Manufacturing Company, Elizabeth,
N. J., a corporation of New Jersey

Application June 20, 1942, Serial No. 447,748

12 Claims. (Cl. 112—199)

This invention relates to sewing machines and more particularly to single-thread chain-stitch sewing machine mechanisms for driving an oscillatory loop-taker or looper.

A primary object of this invention is to provide an extremely high speed looper-actuating mechanism for single-thread chain-stitch sewing machines, whereby the looper has a prolonged dwell prior to the beginning of its loop-seizing movement. By thus providing a dwell in the looper, the needle will be given time to properly throw out its needle-loop for certain seizure by the looper. It is a further object of the invention to accelerate the retracting motion of the looper to hasten the shedding of the needle-loop after the needle has entered it.

Another object of the invention is to provide a particularly compact and light weight looper-actuating mechanism of which all of the elements have been designed so that they may be readily applied to and removed from the sewing machine by the use of the simplest tools and in a short period of time. By thus providing a quickly applicable looper-actuating mechanism, the manufacture and assembly of the sewing machine is greatly facilitated. Furthermore, the machine as thus made facilitates any repair work which may be required during the life thereof.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Referring to the drawings,

Fig. 1 is a front side elevation of a sewing machine incorporating the present invention and showing the base portion of the machine in section.

Fig. 2 is a bottom plan view of the present machine.

Fig. 3 is a vertical section taken substantially along line 3—3 of Fig. 1.

Fig. 4 is a bottom perspective view of a portion of the looper-actuating mechanism shown in Fig. 2.

Fig. 5 is a top plan view of the mechanism shown in Fig. 4.

Fig. 6 is an enlarged view in side elevation of one of the looper elements as it enters the needle-loop.

Figs. 7 to 10, inclusive, are sections taken sub-

stantially along line 1—1 of Fig. 5 and illustrate various stages of movement of the looper actuating mechanism during the stitching cycle.

The sewing machine herewith illustrated as incorporating the present invention comprises a frame including a base 15 providing a cloth-plate 16 from one end of which rises the standard 17 carrying the overhanging bracket-arm 18 terminating at its free end in the head 19. Journaled in the head 19 are the usual presser-bar 20 and endwise reciprocatory needle-bar 21 carrying the needles 22. The presser-bar 20 carries the usual presser-foot 23 with which the usual feed-dog 24 cooperates to feed the work.

15 The bed 15 is closed at the bottom by means of a drip-pan 25 having an oil-sump portion 26 provided therein.

10 The needle-bar 21 has the usual link connection 27 with a crank 28 on the main shaft 29 journaled in the bracket-arm 18 and carrying the balance wheel and belt-pulley 30.

15 Carried by the main shaft 29 is a gear 31 meshing with a gear 31' mounted on a vertical shaft 32 which is suitably journaled in the stand-

ard 17. The lower portion of shaft 32 carries a gear 33 meshing with a gear 34 mounted upon the rear end portion of a shaft 35 which is horizontally journaled in bearings 36 and 37 carried by the base 15 of the frame. As gears 31 and 34 are of one set size and gears 31' and 33 are of another set size the rotation of the shaft 29 will rotate shaft 35 in one to one relation therewith.

20 The lower end of shaft 32 extends into an oil pump unit 38 and the rotation of this shaft is effective to operate the pump so that oil contained in the oil sump 26 will be drawn up through the pump screen 39 and forced through the oil conduits 40, 41 and 42. Conduit 42 circulates the oil into the overhanging bracket-arm of the machine and conduits 41 and 40 conduct the oil to bearings 37 and 43 respectively. For a more detailed disclosure of this oil pump, reference may be made to the U. S. patent to Kaier, No. 2,206,285, July 2, 1940.

25 Eccentrics 44 and 45, carried by the shaft 29 are embraced, respectively, by the pitmans 46 and 47 of which the lower portions are respectively pivotally secured to cranks 48 and 49. Rotation of the shaft 29 will, through the medium of the above noted eccentrics and pitmans, oscillate the two cranks 48 and 49. The crank 48 is secured to the feed advance and return rock-shaft 50, which is suitably mounted in the base 15 and connected at its forward end to the usual feed-bar 51 carrying the feed-dog 24. The crank

49 is secured to the feed-lift rock-shaft 52 also mounted in the base 15 and operatively connected to the feed-bar 51. For a more complete disclosure of this feeding mechanism reference may be made to the above noted Kaier patent.

As may be best seen in Figs. 1 and 5, the base 15 is provided with an aperture 53 for receiving the bearing 37 which is secured therein by means of a set screw 54. Upon an extended end portion of the bearing 37 is mounted a substantially horizontally C-shaped bracket 55 secured thereto by means of set screws 56. Each arm portion of the bracket 55 is provided with a semi-circular recess 57 for supporting a flanged bearing 58 retained by means of a bearing-cap 59 secured to each arm by means of screws 60. Slidably mounted within the two flanged bearings 58 is an endwise reciprocatory rod 61 which is disposed in a direction parallel to the line of feed and parallel to the plane of the cloth-plate 16. The rod 61 is also disposed horizontally transverse to the bed-shaft 35 whereby the longitudinal axes of said shaft and said rod are in substantially the same horizontal plane. Intermediate its ends, the rod 61 is provided with a guideway or channel 62 lengthwise extending at right angles to the longitudinal axis of the rod 61. Depending from the guideway 62 is a member 63 having a slot 64 formed therein for embracing a stub-rod 65 for the purpose of preventing turning of the rod 61 about its longitudinal axis. The stub-rod 65 is rigidly secured within the opposite arm portions of a holder 66 by means of set screws 67. The holder 66 is in turn secured to the hub portion of bracket 55 by a screw 68. As may be seen in Fig. 4, the back side of the guideway portion of the rod 61 is provided with a pair of apertures 99 for the sole purpose of making for a lighter reciprocating unit.

As may be best seen in Fig. 5, the shaft 35 is journaled within the bearing 37 and it extends therethrough to have mounted upon its end portion a rotary disk-crank 69 which is secured to the shaft by means of a set screw 70. Extending from the forward face of the rotary crank 69 is a crank-pin 71 embraced by a wear- or slide-block 72 which snugly enters the guideway 62.

As hereinabove described, the shaft 35 is given a one to one rotary motion with the shaft 29. The crank-pin 71 and the slide-block 72 are therefore given a rotary motion which imparts pure simple harmonic reciprocatory movements to the rod 61. Figs. 8 and 10 show, respectively, the left and right hand dead-center points of the slide-block 72 relative to the guideway 62. It is to be understood that the rod 61 comes to rest momentarily whenever the slide-block is in either of its two dead-center positions, and further, that the rod 61 attains its greatest velocity whenever the slide-block passes through either of its two positions medianly of the dead-center points.

Extending from the forward face of the guideway 62 is a pin 73 upon which one end of a link 74 is pivotally mounted. The other end portion of the link 74 is provided with an aperture 75 entered by a crank-pin 76 of a crank 77 which is mounted upon an end portion of an oscillatory looper-carrying shaft 78. Set screws 79 secure the crank 77 rigidly upon the shaft 78. The inner end portion of the shaft 78 is mounted in the bearing 43 and the outer end portion thereof is similarly mounted in a bearing bracket 80 secured by screws 81 to the underside of the cloth-plate 16. A thrust-collar 82 secured upon the

shaft 78 by screws 83 engages the bearing 43 to cooperate with the hub portion of the crank 77 in preventing endwise movements of the shaft 78. Screws 84 secure the looper-carrier 85, carrying 5 the loop-takers or loopers 86, to the looper carrying or oscillatory shaft 78. In the present case, the loopers 86 are of the non-thread carrying or single-thread chain-stitch type.

As may be best seen from Figs. 2 and 3, the 10 bearing 43 is mounted within the bearing block or bracket 87 and secured therein by means of a set screw 88. The bracket in turn is removably secured directly to the underside of the base 15 by means of screws 89.

15 From the above description it is to be understood that the bracket 55 carries substantially the entire looper-actuating mechanism and that the bracket in turn is merely secured upon the bearing 37. As may be seen from Fig. 1, the upper 20 surface of the bracket 55 engages the underside of the cloth-plate 16, whereby the bracket is prevented from turning about the axis of the shaft 35.

25 In order to remove the loopers and their actuating mechanism from the sewing machine one need only remove the brackets 87 and 89 from the machine base, loosen screws 79 from the crank 77 so that the shaft 78 may be removed therefrom, and then by loosening the screws 56 and 70 30 the main bracket 55 may be backed off from the bearing 37. It is obvious that such an operation requires merely the use of the simplest tools and the expenditure of only a few moments time.

35 As the straight line reciprocatory rod 61 shifts endwise of itself, due to rotation of the rotary crank 69, the lower end of the link 74 is carried back and forth, thus swinging the link about the crank-pin 76 of the crank 77, thereby forcing the crank 77 to oscillate about the axis of and in 40 turn to oscillate the shaft 78. As may be best seen from Figs. 7 to 10 inclusive, the crank 77 and the link 74 form a toggle connection and when these two elements are substantially at right angles to each other, as seen in Fig. 8, the link 74 45 swings about the crank-pin 76 of the crank without appreciably moving the same. Thus a dwell is produced in the oscillatory movement of the crank 77 and consequently in the loopers 86. Furthermore, it is to be seen from Fig. 8, that 50 when the toggle elements are perpendicular to each other the slide-block 72 is at one of its two dead center points thus causing a further dwell in the toggle mechanism. These two dwells are 55 additive as they occur at the same point, and the result is that an extremely long period of dwell is produced in the loopers when they are at the end of their loop-seizing stroke, as illustrated in the view of a looper and its cooperating needle shown in Fig. 8. The needle at this period in the 60 cycle is at the top portion of its stroke.

Figs. 7, 8 and 9 illustrate three successive stages during the dwell-producing portion of a single revolution of the rotary crank 69. The arrows 98 indicate the path and the direction of 65 circular movement of the slide-block 72. It may be seen from Fig. 7 that the slide-block 72 is approaching a dead center point and that the toggle elements 74 and 77 are approaching their right angle positions and thus the dwell period has started. In Fig. 8 as hereinabove noted, the slide-block is at one of its two dead center positions and the toggle elements are substantially perpendicular with each other. Fig. 9 illustrates the mechanism just at the end of the dwell 70 75

period when the slide-block has passed through its dead center position and the toggle elements are no longer in their perpendicular relation. It is to be seen that very little movement has been transmitted to the looper-actuating shaft from the rotary crank during this period, and further, that the rotary crank has passed through a relatively large angle.

It is to be seen that when the slide-block 72 moves from its position shown in Fig. 9 to that shown in Fig. 10, the reciprocating bar 61 will be moved to the right thus imparting an accelerated motion to the toggle elements. The effect of this acceleration on the part of the toggle elements is to accelerate the retracting stroke of the loopers, thus hastening the shedding of the needle-loop and giving the descending needle more time to shorten such loop. In machines of the single-thread chain-stitch type, it is desirable that the needle-loop be shed from the looper as quickly as possible after such loop has been entered by the descending needle, so that the remaining portion of the down-stroke of the needle will be sufficient to shorten the shed needle-loop. It is to be understood that in almost all single-thread chain-stitch machines, including the present device, the thread-carrying needle is adapted to pull thread from the previously formed needle-loop as the needle descends into the work, and thus during the latter portions of the descending needle movements this loop is shortened sufficiently to "set" the same into the work. Therefore the above described accelerated motion of the looper is timed to occur just after the needle has entered the loop, thereby to insure a quick shedding action of the needle-loop after the needle has entered the same. Fig. 10 illustrates the relative positions of the elements just before the loop-seizing stroke of the loopers.

The means for lubricating a portion of the looper-actuating mechanism is only illustrated in Figs. 4, 5 and 7, as it would otherwise complicate the other figures to include it therein and no useful purpose would be accomplished thereby. This lubricating means includes the oil conduit 41 which delivers oil through a duct 90, provided in the frame 15, to a transverse duct 91 which is provided in the shaft 35 and which registers with duct 90 twice during every revolution of the shaft 35 thereby to pick up oil therefrom. This oil is then delivered to the conduit 92 formed longitudinally of the shaft 35 and communicating with a radial duct 93 formed in the rotary crank 69. As the oil is driven under a pressure supplied by the oil pump unit 38, it finds its way from the radial duct 93 to another longitudinal conduit 94 formed in the rotary crank 69 and extending into the crank-pin 71 so as to communicate with a transverse duct 95 also formed in the crank-pin 71. The oil which is delivered to the duct 95 is under sufficient pressure so that it will find its way about the slide-block 72 to thus lubricate the guideway 62. The slide-block 72 is provided with horizontally disposed ducts 95' which will be aligned with the duct 95 periodically to thus deliver a quantity of the oil to conduits 96 formed in each of the two portions of the reciprocating rod 61 which extend away from the guideway 62. The conduits 96 deliver the oil to the transverse ducts 97 which in turn deliver it to the relatively moving surfaces between the flanged bearings 58 and the rod 61.

Having thus set forth the nature of the invention what I claim herein is:

1. A thread-manipulator mechanism for sewing machines comprising, a rotary shaft, a pair of fixed and spaced bearing members, a straight line reciprocating member mounted in said bearing members, means carried by said rotary shaft for imparting simple harmonic motion to said reciprocating member, a loop-taker, and operative connections between said loop-taker and said reciprocating member, said connections including crank and link elements of which one is carried by said reciprocating member and the other is connected to said loop-taker.
- 10 2. A sewing machine looper mechanism comprising, a rotary shaft, a straight line reciprocating member, means including interengaging crank and guideway elements disposed between said rotary shaft and said reciprocating member for imparting simple harmonic motion to the latter member, a loop-taker, and operative connections between said loop-taker and said reciprocating member, said connections including crank and link elements of which one is carried by said reciprocating member and the other is connected to said loop-taker.
- 20 3. A sewing machine looper mechanism comprising, a rotary shaft, a straight line reciprocating member, operative connections between said rotary shaft and said reciprocating member for imparting simple harmonic motion to said reciprocating member, said operative connections including interengaging rotary crank and guideway elements, a loop-taker, and means interposed between said reciprocating member and said loop-taker for actuating the latter, said means including interconnected crank and link elements one of which is carried by said reciprocating member and the other is connected to said loop-taker, said interconnected crank and link elements being arranged to be disposed substantially at right angles to each other when said rotary crank is at one of its two dead-center points relative to said guideway.
- 30 4. A sewing machine looper mechanism comprising, a rotary shaft, a rotary crank carried and actuated by said rotary shaft, a straight line reciprocating member, said reciprocating member being formed with a guideway lengthwise extending at right angles to the longitudinal axis of said reciprocating member, said rotary crank being in engagement with said guideway for imparting simple harmonic motion to said reciprocating member, an oscillatory loop-taker, and means carried by said reciprocating member and connected to oscillate said loop-taker, said rotary crank being arranged to be at one of its two dead-center points relative to said guideway when said loop-taker is at the end of its loop-seizing stroke.
- 40 5. A sewing machine looper mechanism comprising, a rotary shaft, a rotary crank carried and actuated by said rotary shaft, a straight line reciprocating member, said reciprocating member carrying a guideway lengthwise extending at right angles to the longitudinal axis of said member, said rotary crank being in engagement with said guideway for imparting simple harmonic motion to said reciprocating member, a loop-taker, and operative means connecting said reciprocating member and said loop-taker, said operative means including interconnected crank and link elements which are arranged to be disposed substantially at right angles to each other when said rotary crank is at one of its two
- 50
- 60
- 70
- 75

dead-center points relative to said reciprocating member.

6. In a sewing machine having a base-portion including a cloth-plate, a rotary shaft carried by said base-portion and beneath said cloth-plate, a straight line reciprocating member disposed beneath said cloth-plate, means carried by said rotary shaft for imparting simple harmonic motion to said reciprocating member, an oscillatory looper-carrying shaft disposed in parallel relation with said rotary shaft, a looper, a link element having one end thereof pivotally secured directly to said reciprocating member, and a crank carried by said looper-carrying shaft and connected to said link element.

7. In a sewing machine having a base portion including a cloth-plate, a rotary shaft carried within said base portion and beneath said cloth-plate, a rotary crank carried by said shaft, a straight line reciprocating member disposed beneath said cloth-plate and being adapted to move in simple harmonic motion, the longitudinal axis of said rotary shaft and said reciprocating member being contained in the same plane, said reciprocating member being provided with a guideway lengthwise extending at right angles to the longitudinal axis of said member, said rotary crank being in operative engagement with said guideway, for reciprocating said member, a looper, an oscillatory looper-carrying shaft disposed in parallel relation with said rotary shaft, and means connecting said reciprocating member to said looper-carrying shaft, said means including a toggle device causing the looper to have a prolonged dwell at the end of its loop-seizing stroke.

8. A single-thread chain-stitch sewing machine comprising a frame including a base, a rotary shaft journaled in said base, at least one bearing removably secured to said base, an oscillatory shaft mounted in said bearing and being disposed in parallel relation with said rotary shaft, a non-thread carrying looper mounted upon said oscillatory shaft, a bracket removably secured to said base, looper-actuating mechanism carried by said bracket, said looper-actuating mechanism being adapted to be connected to said oscillatory shaft, and means carried by said rotary shaft for engaging and actuating said looper-actuating mechanism.

9. A single-thread chain-stitch sewing machine comprising a frame including a base, a rotary shaft journaled in said base, an oscillatory shaft mounted within said base and disposed in parallel relation with said rotary shaft, a non-thread carrying looper carried on said oscillatory shaft, a bracket removably secured to

the underside of said base and affording a bearing-support, an oscillatory looper-actuating mechanism carried by said bracket, said looper-actuating mechanism including a straight line reciprocating member and toggle means actuated by said reciprocating member and adapted to be connected to said oscillatory shaft, and means carried by said rotary shaft for engaging and imparting simple harmonic motion to said reciprocating member.

10. A thread-manipulator mechanism for sewing machines, comprising, a rotary shaft, a pair of fixed and spaced bearing members, a straight line reciprocating member mounted in said bearing members, means carried by said rotary shaft for imparting simple harmonic motion to said reciprocating member, an oscillatory looper, and operative connections between said looper and said reciprocating member, said connections including means for producing a dwell in the movement of the loop-taker, the period of said dwell occurring whenever the reciprocating member reaches one of its two direction-changing points.

11. A thread-manipulator mechanism for sewing machines, comprising, a rotary shaft, a pair of fixed and spaced bearing members, a straight line reciprocating member mounted in said bearing members, said reciprocating member and the longitudinal axis of said rotary shaft being contained in the same plane, means carried by said rotary shaft for imparting simple harmonic motion to said reciprocating member, an oscillatory looper, and operative connections between said looper and said reciprocating member, said connections including means for producing a dwell in the movement of the loop-taker.

12. In a sewing machine having a base-portion including a cloth-plate, a rotary shaft carried by said base-portion and beneath said cloth-plate, a straight line reciprocating member disposed beneath said cloth-plate, the longitudinal axes of said rotary shaft and said reciprocating member being contained in the same plane, means carried by said rotary shaft for imparting simple harmonic motion to said reciprocating member, an oscillatory looper-carrying shaft disposed in parallel relation with said rotary shaft, a looper, a link element having one end thereof connected to said reciprocating member, and a crank carried by said looper-carrying shaft and connected to said link element, said link element being arranged to be substantially at right angles to said crank when said reciprocating member reaches one of its two direction-changing points.

ANDREW B. CLAYTON.
